UNITED STATES PATENT OFFICE.

PETER LYMBURNER ROBERTSON, OF HAMILTON, ONTARIO, CANADA.

SCREW-BLANK-HEADING MACHINE.

1,003,657.

Specification of Letters Patent. Patented Sept. 19, 1911.

Continuation in part of application Serial No. 401,224, filed November 8, 1907. This application filed February 12, 1910. Serial No. 543,648.

To all whom it may concern:

Be it known that I, PETER LYMBURNER ROBERTSON, of the city of Hamilton, in the Province of Ontario, Dominion of Canada, have invented certain new and useful Improvements in Screw-Blank-Heading Machines; and I do hereby declare that the same is a full, clear, and exact description of the same.

10 My invention relates particularly to cold process headers, and it has for its object to provide tools for a machine of this type which will produce a blank having a non-crystallized head with a socket of effective 15 depth.

It has been proposed to punch in the head of a screw blank a slot with closed ends and a slot in the form of a cross in plan view and triangular in longitudinal section.

20 The defects in these methods are that in punching the first mentioned slot the metal is not caused to flow evenly, and an effective depth cannot be produced without the metal in advance of the punch being crystallized thus fatally weakening the screw 25 at its neck, and the slot produced is too shallow to afford an effective hold for the screw driver; while in punching the second mentioned slot the metal flows unevenly and 30 the form produced does not afford an effective hold for the screw-driver.

The present machine embodies means adapted to form the head of a screw blank by punching a socket or recess in the end 35 of a piece of wire, by means of a punch presenting a male die of square cross section and all the sides whereof are of equal area and converge at a very slight angle while the end converges sharply to a point.

40 The punch is reversible and formed at both ends with male dies such as just described.

A bumper block of relatively soft metal is provided and has a chamber at one end, 45 and such punch and block are set in a hammer, the chamber in the bumper block accommodating the die on the inner end of the punch. For full comprehension, however, of my invention reference must be had 50 to the accompanying drawings, forming a part of this specification, in which similar reference characters indicate the same parts and wherein—

Figure 1 illustrates the hammers and 55 matrix and a part of the machine in which

they are mounted, a piece of wire from which the screw is to be made being located in the matrix ready to have the screw-head formed; Fig. 2 illustrates the matrix, first hammer and screw blank at the completion 60 of the first blow; Fig. 3 illustrates the matrix, second hammer, and screw blank at the completion of the second blow which completes the socket, thus filling the matrix to its full capacity and forming and facing 65 the head; Fig. 4 is an enlarged detail view of the completed head; Figs. 5 and 6 are detail perspective views of the punch and bumper blocks; Fig. 7 is an enlarged detail 70 sectional view of the male die; Fig. 8 is a detail face view of the male die. Fig. 9 is a side elevation partly in sectional view taken on line A A. Fig. 4 and illustrating a complete screw.

The matrix *b*, and first and second hammers *c* and *d*, respectively, are mounted and operated in the usual way, the second hammer carrying the punch *e* which is reversible and presents at each end a male die *f* of square cross-section and all the sides 80 whereof are of equal area and as before mentioned converge at a very slight angle, while the end converges at an angle of forty five (45°) degrees and terminates in a point preferably of pyramidal form. The 85 bumper block *g* of relatively softer metal is located behind the punch *e* and the chamber to accommodate the die on the rear side of the punch is indicated at *i*, the opposite end of such bumper block being without 90 opening of any kind and affording means whereby, upon the set screw *j* being loosened, and a pin being inserted through a hole *s* in the hammer the block and punch can be driven out of the hammer when it is desired 95 to reverse or exchange the punch when the die is worn or a socket of different dimensions is to be punched.

The knock-out-pin, indicated at *h*, is operated in the usual manner. 100

The best results are obtained by making the die, punch block, bumper block and the hammer carrying them in substantially the proportions illustrated, the advantages being that the die will not break off of the 105 punch block as readily as it would from the relatively large body of the hammer if formed thereon; while the bumper block being of relatively softer material acts as a cushion, and the slight measure of play be- 110

tween the punch and bumper blocks and such blocks and the hammer relieves any side strains due to uneven screw blank heads.

- 5 The method of punching the socket and simultaneously forming the head consists in subjecting the piece of wire *k* (Fig. 1) to two blows, the first (Fig. 2) upsetting the protruding end and the second (Fig. 3) 10 punching the socket and thereby forming and facing the head, an incidental effect being that the edge of the mouth of the socket is flattened off as shown.

As the point of the punch enters the 15 partially formed head, the spreading of metal caused thereby is continued by the sides although to a less extent in proportion to the distance traveled, and, besides producing a head with practically perfect 20 co-noidal surface and flat face, forms a socket the uniform and converging walls of which insures so effective a connection between the screw and its driver that such screw may be carried upon the point of the driver, while a 25 proper alinement of the two being maintained the danger of the driver slipping is completely obviated. After the punching of the socket and forming of the head thereby, the blank is threaded and the screw finished 30 in the usual way.

This method of producing screws has many advantages over cold-process methods of forming screw-heads heretofore unknown, in that the metal displaced as the socket is 35 formed fills the matrix without causing defective distortion or crystallization. This is owing to the uniform spreading of the metal laterally from all sides of the punch by its sharply converged point and slightly 40 converged sides; the object being to spread the metal uniformly throughout the space between the punch and the wall of the matrix, and avoid forcing it in front of the punch which would cause crystallization.

45 While I have described my method of pro-

ducing the screw blank I do not herein claim same as such will form the subject matter of a separate application.

What I claim is as follows:—

1. In a screw heading apparatus, the combination with a matrix block having a perforation to accommodate the length of stock from which the screw is formed, of a punch carrying a die having a body portion and a pointed portion, the body portion being square in cross section and of a length less than the depth of the head of the screw being formed and the pointed portion being of pyramidal form and also square in cross section. 50

2. In a screw heading apparatus, the combination with a matrix block having a perforation to accommodate the length of stock from which the screw is formed, of a punch carrying a die having a body portion and a pointed portion, the body portion being square in cross section, slightly converging toward the pointed portion and of a length less than the depth of the head of the screw being formed and the pointed portion 65 being of pyramidal form and also square in cross section. 70

3. In a screw heading apparatus, the combination with a matrix block having a perforation to accommodate the length of stock 75 from which the screw is formed, of a punch carrying a die having a body portion and a pointed portion, the body portion being square in cross section and of a length less than its width and the pointed portion being of pyramidal form and also square in cross section. 80

In testimony whereof, I have signed my name to this specification, in the presence of two subscribing witnesses.

PETER LYMBURNER ROBERTSON.
